UNITED STATES PATENT OFFICE.

JOSEPH G. MOOMY AND JOSEPH H. MOOMY, OF ERIE, PENNSYLVANIA, ASSIGNEES OF ONE-THIRD TO HARRY E. MOOMY, ONE-THIRD TO MARY H. MOOMY, OF ERIE, PENNSYLVANIA, AND ONE-THIRD TO SAID JOSEPH H. MOOMY.

APPARATUS FOR AND METHOD OF MIXING PLASTIC MATERIALS.

Application filed March 24, 1922. Serial No. 546,258.

To all whom it may concern:

Be it known that we, JOSEPH G. MOOMY and JOSEPH H. MOOMY, citizens of the United States, residing at Erie, in the county 5 of Erie and State of Pennsylvania, have invented new and useful Improvements in Apparatus for and Methods of Mixing Plastic Materials, of which the following is a specification.

10 This invention is designed to mix plastic materials, particularly rubber. Where certain ingredients are combined with the rubber, such as lamp black, the open mills give a great deal of trouble in that the black is sifted through the entire plant. In addition to this the mixing in our present method and invention is more varied than with the ordinary mixers used. In carrying out our invention we place the batch in a cylinder between 15 two working surfaces, one at least of which is rotated and force these two surfaces toward each other under pressure. In this way the batch is rotated and has a tendency to move toward the outer periphery 20 which varies the turning movement of the mass so as to thoroughly mix it.

The apparatus is illustrated in the accompanying drawings as follows:—

Fig. 1 shows an elevation of the machine.

30 Fig. 2 a central vertical section through the machine.

Fig. 3 a section on the line 3—3 in Fig. 2.

Fig. 4 a section on the line 4—4 in Fig. 3.

1 marks the base, 2 a cylinder carrying 35 head, 3 a flange on the head 2 which is secured to the base by means of bolts 4. A cylinder 5 extends from the head 2. A non-rotative mixing member 6 is slidingly mounted in the cylinder 5 and has a working surface 7. A plunger 8 extends from the member 6 and this is provided with a cup 9 at its end forming a closure with the walls of the cylinder 10 in which the plunger operates. The plunger is provided with 40 a groove 11 which is engaged by a spline 12 so as to lock the member 6 against rotation. Fluid, ordinarily air, is delivered through the passage 13 from a supply pipe 14 to force the member 6 upwardly so as to place 45 pressure on the batch.

An upper rotating member 15 opposes the member 6 and has a corrugated working surface 16. The member 15 operates against a ball bearing 17 which takes the thrust

against the member and has a shank 18^a 55 which operates in a bearing 18 in a cover 18^b on the cylinder. A gear 19 is fixed by a key 20 on the shank, or shaft 18^a and meshes with a gear 21. The gear 21 is fixed on the shaft 22 by a key 23. The shaft 22^b 60 is journaled in bearings 24 carried by brackets 25 extending from the head 2 and cylinder 5. A bevelled gear 26 is fixed on the lower end of the shaft 22 by means of a key 27 and meshes with a gear 28 fixed on a key 65 29 on a horizontal drive shaft 30. The shaft 30 is journaled in bearings 31 in the base 1. It will readily be seen that as the shaft 30 is rotated this motion is communicated through the mechanism described to 70 the member 15. In operation, therefore, the batch is placed between the two surfaces 7 and 16. The upper member is rotated. The lower member is lifted under pressure. The batch, therefore, is subjected to the rotary 75 movement between the surfaces and tends to move between the outer periphery of these surfaces, this movement giving to the batch a secondary turning movement so that there is a variation in the mixing effect which results in a homogeneous thoroughly mixed mass.

The member 15 has a cooling chamber 32 and cooling water is carried to this through a pipe 33 and discharged through an opening 34 in the shank 18^a.

An opening 35 is made in the walls of the cylinder to the space between the members 6 and 15 and this opening is closed by the doors 36 and 37 mounted on hinges 38. The 90 lower door has a lower off-set 39 forming a seat with a surface 40 on the edge of the door opening, the upper edge of the door 37 being provided with a seating surface 41 which engages a surface 42 of the door 36. 95 The door 36 also has a surface 43 engaging a surface 44 on the edge of the opening to the cylinder. The doors are provided with the fastening lugs 45 in which eye bolts 46 are arranged for clamping the doors in 100 closed position. By this method both doors are sealed and the doors may be opened separately as required.

The doors are provided with the cooling chambers 47 to which water is communicated 105 by way of pipes 48 and discharged by way of pipes 49, these pipes having the connections 48^a which permit of their being dis-

connected so as to swing the doors. The cylinder is also provided with a cooling chamber 50 which is supplied through pipes 51, the discharge being by way of a pipe 52.

5. What we claim as new is:—

1. In a mixing machine, the combination of a mixing cylinder; mixing members in the cylinder having working faces at right angles to the axis of the cylinder; and means 10 for rotating one of said members and for moving one of them axially to compress an interposed batch.

15. 2. In a mixing machine, the combination of a mixing cylinder; mixing members in the cylinder having corrugated working surfaces at right angles to the axis of the cylinder; and means for rotating one of said members and for moving one of said members axially to compress an interposed batch.

20. 3. In a mixing machine, the combination of a mixing cylinder; mixing members in the cylinder having working faces at right angles to the axis of the cylinder; means for rotating one of said members; and means 25 for moving the other of said members axially to exert pressure on an interposed batch.

30. 4. In a mixing machine, the combination of a mixing cylinder; mixing members in the cylinder having working faces at right angles to the axis of the cylinder; means for rotating one of said members and for moving one of them axially to compress an interposed batch; and means for cooling one 35 of said members.

35. 5. In a mixing machine, the combination of a mixing cylinder; mixing members in the cylinder having working faces at right angles to the axis of the cylinder; means for rotating one of said members and for moving one of them axially to compress an interposed batch; and means for cooling the 40 cylinder walls.

45. 6. In a mixing machine, the combination of a mixing cylinder; mixing members in the cylinder having working faces at right angles to the axis of the cylinder; means for rotating one of said members and for moving one of them axially to compress an interposed batch; and means for cooling one 50 of said members and the cylinder walls.

55. 7. In a mixing machine, the combination of a mixing cylinder; mixing members in the cylinder having working faces at right angles to the axis of the cylinder; means for 60

rotating one of said members and for moving one of them axially to compress an interposed batch; and a door in the cylinder wall leading to the space between said members.

8. In a mixing machine, the combination of a mixing cylinder; mixing members in the cylinder having working faces at right angles to the axis of the cylinder; means for rotating one of said members and for moving one of them axially to compress an interposed batch; and a circumferentially arranged door leading to the space between said members.

9. In a mixing machine, the combination of a mixing cylinder; mixing members in the cylinder having working faces at right angles to the axis of the cylinder; means for rotating one of said members and for moving one of them axially to compress an interposed batch; a door in the cylinder wall leading to the space between said members; and means for cooling said door.

10. In a mixing machine, the combination of a mixing cylinder; mixing members in the cylinder having working faces at right angles to the axis of the cylinder; means for rotating one of said members and for moving one of them axially to compress an interposed batch; a circumferential opening in the cylinder having circumferentially extending door seats thereon; and two doors for closing the opening, one of said doors having an inwardly faced seat for engaging the seat on the cylinder and an outwardly faced seat and the other of said doors having two inwardly faced seats for engaging one seat on the cylinder and the outwardly faced seat on the other of said doors.

11. The process of mixing plastic material which consists in inclosing and confining it circumferentially and axially and subjecting it to pressure rotatively applied in an axial direction.

12. The process of mixing plastic material which consists in inclosing and confining it circumferentially and axially and subjecting it to pressure rotatively applied in an axial direction, and varying the temperature of the plastic through the confining medium.

In testimony whereof we have hereunto set our hands.

JOSEPH G. MOOMY.
JOSEPH H. MOOMY.
